Application filed February 6, 1901. Serial No. 46,276. Term of patent 3½ years.

To all whom it may concern:

Be it known that I, ERWIN EDWARDS, a citizen of the United States, residing at Greenwich, in the county of Fairfield and State of Connecticut, have invented and produced a new and original Design for the Back of a Game-Counting Book, of which the following is a specification.

This invention relates to a new and original design for the back of a game-counting book; and the essential feature resides in the design, as illustrated in the accompanying drawing, which shows a plan view of the back embodying the design.

The design is characterized by a body 1, having a series of three hearts 2, arranged

with their pointed ends downwardly and all in longitudinal alinement. Extending longitudinally of the body and centrally piercing all the hearts is an arrow 3.
